(57) **CLAIM**

The ornamental design for an electrical cable termination with pull tabs and through holes, as shown and described.

DESCRIPTION

FIG. 1 is a front perspective view of an electrical cable termination with pull tabs and through holes, showing my new design;

FIG. 2 is a back perspective view thereof;

FIG. 3 is a left side elevation view thereof;

FIG. 4 is a front side elevation view thereof;

FIG. 5 is a right side elevation view thereof;

FIG. 6 is a back side elevation view thereof;

FIG. 7 is a top plan view thereof; and,

FIG. 8 is a bottom plan view thereof.

The broken lines shown represent portions of the electrical cable termination with pull tabs and through holes that form no part of the claimed design.

1 Claim, 5 Drawing Sheets
